DIRECTIONAL AERIAL

Fred Woods, Richmond, Surrey, England, assignor to Radio Corporation of America, a corporation of Delaware

Application December 3, 1930, Serial No. 499,619
In Great Britain December 12, 1929

8 Claims. (Cl. 250—33)

This invention relates to directional aerial systems and, although not limited to its application thereto, is particularly suitable for use in connection with direction finding installations on board ship.

As is well known, it is common practice in direction finding installations to provide a directional aerial system for ascertaining the direction of a received signal and an additional open aerial for ascertaining the "sense" of that direction. In many places, for example, on board ship, the additional open aerial constitutes an undesirable complication since it occupies valuable room and is sometimes difficult to install satisfactorily.

According to this invention, a directional aerial system comprises directional frame aerial windings for ascertaining the direction of a received signal and means constituted by a screen or screens about said directional frame aerial windings for ascertaining the "sense" of said direction.

The invention is illustrated in the accompanying schematic drawing in which Figure 1 shows one general arrangement in accordance with this invention, while Figure 2 shows a preferred detail modification suitable for incorporation at the base of the pedestal which forms part of the apparatus shown in Figure 1.

Referring to Figure 1, this shows a form of construction as applied to a so-called Bellini-Tosi frame aerial system suitable for use on ship board. Apparatus comprises a hollow pedestal 1 mounted upon insulating material 2 and carrying on the top a directional aerial system consisting of a pair of mutually perpendicular coils 3, 4, as usually provided in the well known Bellini-Tosi system. The mutually perpendicular coils are enclosed within and screened by metal and preferably weatherproof tubes 5, 6 of usual construction which are connected together at the top where they cross and are insulated from one another at the bottom where they cross.

The top junction point of the tubular screens is constituted by a suitable boxlike structure 7 which serves to provide mechanical support for the screens, said boxlike structure carrying a downwardly projecting rod 8 which terminates at its end in a similar boxlike structure 9 which supports the coil screens at their lower crossing at which they are insulated from one another. The rod is connected down through the pedestal to a connection point 10 which thus constitutes electrically the connection point of the screen system.

55 The leads 11, 12, 13, 14, from the direction finding

windings are similarly brought down inside the pedestal.

When it is desired to take directional readings, the connection point for the screen system is left earthed or insulated, i. e., unconnected, and the aerials are utilized in the usual way. When it is desired to take "sense" readings the connection point for the screen system is connected to earth through an appropriate phasing circuit by any convenient form of switch gear.

Preferably the frame aerials, pedestal, leads, and associated amplifier are provided with continuous screening. Such screening is very easy to effect in the described construction, for example, as shown in Figure 2, by taking the leads 15 at the base of the pedestal through a hole 15 in the side thereof, and through a screening tube 16 to the usual screened amplifier 17, the tube, amplifier screen and pedestal being thus continuous and totally enclosing the electrical circuits and connections.

It is found that with such continuity of screening comparative immunity from induction and other electrical noises is obtained since with the described arrangement all points of the screening system are maintained at substantially the same electrical level. It is not in practice necessary to earth the screens though, of course, this may in some cases be desirable if convenient. Again with such screens it is not in practice necessary that the pedestal should be mounted upon insulation though again this may be found desirable if convenient.

Having now particularly described and ascertained the nature of my said invention and in what manner the same is to be performed, I declare that what I claim is:

1. A unilateral signal absorption system including means for insuring that the energy absorbed thereby will be truly characteristic of the system's position relative to the source of said signals comprising, two closed windings of a plurality of turns, a screen comprising two metallic tubes arranged at right angles to each other completely enclosing each of said windings, said metallic tubes completely electrostatically shielding said windings and substantially completely physically enclosing said windings, said windings being open to magnetic lines of force, means for rotatably mounting said screen on an insulated base, means for connecting said closed windings to a receiving set, and means for obtaining a vertical aerial effect comprising a central metallic rod forming a lead symmetrically connected to

- said screen and symmetrically arranged with respect to said first named leads.
2. A directional aerial system comprising two directional loop aerials enclosed within metallic tubes, said tubes mounted upon a hollow metallic pedestal, both tubes and pedestal comprising an electrical shield for said directional aerial system, said loop aerials arranged at right angles to each other, the lower portion of said loop aerial being supported on said hollow metallic pedestal by a box-like insulating member, and an upper metallic box-like member providing a junction point for said loop aerials, said upper member having a depending metallic rod, said rod being mechanically secure but electrically insulated from said lower insulating member.
- 5 10 15 20 25 30 35 40 45 50 55
3. A directional aerial system comprising a pair of crossed frame closed aerial windings, shielding means for said windings comprising metallic tubes electrically and mechanically connected together at one crossing point and electrically insulated but mechanically secured together at the other crossing point, means for connecting said windings to a receiver, and a metal rod passing diametrically across the frame closed aerials and between the two crossing points thereof, said metal rod being mechanically secured but electrically insulated from the last mentioned crossing point so as to act as a lead for said shielding means.
4. A directional aerial system comprising two directive loop aerials arranged at right angles to each other and enclosed within metallic tubes, said tubes being mounted on a hollow metallic pedestal, both tubes and said pedestal comprising an electrical shield for said directional aerial system, an amplifier for said system, a plurality of connecting leads for connecting said loops and the amplifier passing through said pedestal, means for providing a vertical aerial effect for said system, comprising a central lead electrically connected to the top of said loops and mechanically secured but electrically insulated at the bottom of said loops and passing through said pedestal and symmetrically disposed with respect to the first mentioned leads so as to provide the vertical aerial effect for said directional system.
- 30 35 40 45 50 55
5. A directional aerial system comprising two directional loop aerials arranged at right angles to each other and enclosed within metallic tubes, said tubes mounted upon a hollow metallic pedestal, one of said loops being a larger diameter than the other, both tubes and pedestal comprising an electrical shield for said directional aerial system, the lower portion of said loop aerial being supported on said hollow metallic pedestal by a box-like insulating member, and an upper
- metallic box-like member providing a junction point for said loop aerials, said upper member having a depending metallic rod, said rod being mechanically secure but electrically insulated from said lower insulating member.
6. A directional aerial system comprising two directional loop aerials enclosed within metallic tubes, said tubes being mounted upon a hollow metallic pedestal, both tubes and pedestal comprising an electrical shield for said directional aerial system, a plurality of connecting leads for connecting said loops with a receiver and passing through said pedestal, said loop aerials arranged at right angles to each other, the lower portion of said loop aerials being supported on said hollow metallic pedestal by a box-like insulating member, and an upper metallic box-like member providing a junction point for said loop aerials, said upper member having a depending metallic rod, said rod being mechanically secure but electrically insulated from said lower insulating member.
- 10 15 20 25 30 35 40 45 50 55
7. A directional aerial system comprising a pair of crossed frame closed aerial windings mounted upon a hollow metallic pedestal, shielding means for said windings comprising metallic tubes electrically and mechanically connected together at one crossing point and electrically insulated but mechanically secured together at the other crossing point, a plurality of connecting leads for connecting said loops with a receiver passing through the lower portion of said pedestal and a central lead electrically connected to the upper crossing point of said loops and mechanically secured but electrically insulated at the lower crossing point of said loop and passing through said pedestal and symmetrically arranged with respect to the first mentioned leads so as to provide a vertical aerial effect for said directional system.
- 30 35 40 45 50 55
8. A directional aerial system comprising two directive loop aerials arranged at right angles to each other and enclosed within metallic tubes, said tubes being mounted on a hollow metallic pedestal, both tubes and said pedestal comprising an electrical shield for said directional aerial system, a central lead electrically connected to the top of said loops and mechanically secured but electrically insulated at the bottom of said loops and passing through the center portion of said pedestal so as to provide a lead for the said electrical signal.
